BIRD FEEDER

Jack E. Pregont, 1168 Columbus Ave., Janesville, Wis.

Filed Apr. 5, 1963, Ser. No. 74,319

Term of patent 3½ years

(Cl. D31—2)

The undisclosed side of FIGURE 1 is substantially the same in appearance as the side shown in said figure.

I claim:

The ornamental design for a bird feeder, as shown and described.
